SOAP TRIMMER

Earl J. Reddert, Madison, and William Sartorius,
Summit, N. J., assignors to Colgate-Palmolive-
Peet Company, Jersey City, N. J., a corporation
of Delaware

Application March 21, 1944, Serial No. 527,504

6 Claims. (Cl. 25—106)

1

This invention relates to a device for pre-positioning soap blanks on feed conveyor belts of a soap press, and, more particularly, to a soap trimmer.

It has long been the custom in the soap industry to introduce a rectangular or cylindrical blank of soap of much smaller dimensions into the soap press die box. In making a milled toilet soap, for example, a strip of the milled soap, generally having either a substantially rectangular or circular cross section, is extruded continuously from a plodder. This strip is cut, for example in an automatic cutter, into short blanks having the form of rectangular parallelepipeds or right cylinders. When such blanks are pressed in the die box, there is great distortion of the soap fibres resulting from the very considerable flow necessary to shape the blank to conform with the dies. This distortion is evidenced by the stretched appearance of the lettering on the bar, the lines of cleavage of the soap within the bar, and the closure marks on the ends.

We have found that soap blanks should be sized and shaped to fit the die box of the soap press as closely as possible. In accordance with the present invention, the soap blank, before entering the die box, is trimmed to approximately the size, shape and contour of the finished cake. The apparatus embodying the present invention is particularly adapted for use in combination with an automatic soap cutter, for cutting the strip extruded from a plodder into approximately correct size, and an automatic press for giving the trimmed cake the desired final shape and finish.

It is among the objects of the present invention to provide a machine for trimming soap to form blanks sized and shaped to fit the die box of a soap press as closely as practicable, whereby the blanks may be readily pressed into finished cakes without excessive distortion and strain and with a minimum of scrap soap.

A further object of the invention is to provide means for converting a single conveyor line of soap or other articles into two conveyor lines on which the articles will have a desired spacing.

Other objects and advantages of the invention will be apparent from the following detailed description, taken in conjunction with the drawings, in which Fig. 1 is a fragmentary isometric projection showing the essential elements of the machine, Fig. 2 is a fragmentary vertical sectional view of the line 2—2 of Fig. 3, and Fig. 3 is a fragmentary horizontal sectional view along the line 3—3 of Fig. 2.

2

Referring now more particularly to the drawings, the apparatus of the invention comprises two side frames, only one of which is shown in Fig. 1 of the drawings and which is designated by reference numeral 2. The side frames are connected at the top by cross bars 4 and 6. On a shaft 8, suitably journaled in the side frames 2, is mounted a pulley 10 around which a continuously movable conveyor belt 12 is provided centrally between the side frames for feeding a cut bar of soap into the machine. This is best seen in Fig. 2, where the relative positions of pulley 10 and belt 12 are indicated in dot-dash lines, and in Fig. 3. It will be understood that a similar pulley (not shown) is provided at the other end of the conveyor belt 12.

At each side of the feed conveyor is mounted a chute 14 secured to but spaced from the side frame by brackets 16. The chute preferably is made in two pieces and comprises a channel section 17 and a removable cover 18. Near the top of the chute 14 and just above the level of the conveyor belt 12, the chute side walls are provided with aligned openings 20. Trimmer elements or dies 21 are secured within the chute. The trimmer elements may comprise cutter supports 22 on which cutter blades 24 are removably fastened by machine screws 26. The trimmer elements may be individually mounted at each corner of the openings 20, or they may be mounted on a frame and removably positioned as a unit within the chute. Several exchangeable sets of trimmer elements for cutting blanks of different sizes and shapes may be provided to adapt the machine for trimming a variety of blanks. A stop 27 is provided, as illustrated in Fig. 3, above the conveyor belt 12 and in line with articles moving toward it on the belt. A convenient method of mounting is to secure the stop 27 to the removable cover 18 on one of the chutes as illustrated in Fig. 3. The stop preferably is made adjustable for stopping the line of untrimmed soap blanks at the desired location in alignment with the trimmer elements 21.

45 A cross head 28 is reciprocally mounted on a support rod 30 and cross bar 4 above the tops of the chutes 14. Secured to the cross head is a soap pusher 32, of inverted T-shape, the head of the pusher being about the size of the untrimmed soap blank. The cross head carries at one side a rack 34 meshing with a gear segment 36 mounted on an oscillating shaft 38 journaled in the cross bar 4.

50 Take-away or delivery conveyors 39 are provided between the chute 14 and the side frame

2 at each side of the machine, just below the level of the aligned openings 28. These conveyors comprise a shaft 48, suitably journaled in the side frames 2, on which pulleys 42 are mounted. Conveyor belts 44 run around the pulleys 42. Only one set of pulleys 42 is shown in the drawings, it being understood that similar pulleys are provided at the other end of the conveyor. The take-away conveyors 39 may carry the trimmed soap blanks directly to the soap press, but in many cases the distance separating the take-away conveyors 39 is greater than the width of the die box of the press. In such cases, it is advantageous to provide additional conveyor belts which are spaced apart a distance corresponding with the width of the die box. Such conveyors may comprise a shaft 48, suitably journaled in the side frames 2, on which pulleys 48 are mounted. Similar pulleys (not shown) are provided on the soap press at the other end of the conveyor. Conveyor belts 50 are mounted on these pulleys 48. Means (not shown) are provided for transferring soap blanks to conveyor 50 from conveyor 39.

Means (not shown) are provided for driving the rotating shafts 8, 48 and 46 and for oscillating the shaft 38 in timed relation. The rotating shafts may all be driven at the same speed or, if desired, the shafts 48 and/or 46 may be driven at a speed different from that of shaft 8.

Operation

A series of untrimmed blanks of soap, e. g., from an automatic soap cutter, are carried by the feed conveyor belt 12 into the machine until the first blank strikes the stop 27. At this time the gear segment 36 oscillates to reciprocate the cross head 28. The soap pusher 32 engages the blank against the stop and pushes it through the opening 28 in the removable cover 18 of one of the chutes 14 into the trimmer elements 21. As soon as the soap pusher has reciprocated out of the line of the other untrimmed blanks on the conveyor belt 12, the line of blanks advances until the lead blank strikes the stop 27. The shaft 38 then oscillates in the other direction, reciprocating the cross head and pusher in the other direction, whereby the lead soap blank is pushed through the opening 28 in the removable cover 18 of the other chute 14 into the trimmer elements 21 therein. The line of blanks on the conveyor belt 12 advances, as already described, until the lead blank engages the stop 27. The shaft 38 now oscillates in the direction first described, causing the soap pusher 32 to urge a second untrimmed blank through the opening 28 of the first mentioned chute and eject the first blank from the trimmer elements and deposit it on the take-away conveyor 39. On its return stroke, the pusher forces a second untrimmed soap blank into the trimmer elements of the second mentioned chute and ejects the blank which is held in the trimmer onto the take-away conveyor on that side of the machine. In passing through the trimmer elements 21 in the chutes 14, the blanks are trimmed the desired amount to provide a trimmed blank corresponding as closely as practicable to the shape of the die. The scrap soap which is trimmed from the blanks falls down through the chutes to receptacles (not shown), and may then be reworked.

It will be seen that feed conveyor 12 and each delivery conveyor 39 are spaced apart a distance at least equal to the thickness of a soap bar blank and that it requires at least two strokes of pusher 32 in each direction to transfer a soap blank be-

tween the conveyors, the first stroke pushing the blank into the trimmer die 21 and the succeeding stroke in the same direction causing a succeeding blank to displace the first blank through the die.

The apparatus may be used as a pre-positioner for soap blanks without trimming where the shape of the untrimmed blanks approximates the shape of the die closely enough for satisfactory operation. It will be understood, of course, that apparatus designed simply as a pre-positioner would not require the chutes 14 and the soap trimmer elements 21.

Although the apparatus has been described in connection with certain specific embodiments, it will be understood that modifications and variations are contemplated within the scope of the following claims.

We claim:

- 20 1. Apparatus for automatically shaping blanks of soap or the like preliminary to die pressing each blank comprising a continuously movable feed conveyor for advancing a close succession of pre-cut blanks into said apparatus, a take-away conveyor at one side of the feed conveyor, a positioning stop in the path of the blanks on the feed conveyor, means for laterally transferring the blank on the feed conveyor which is in contact with said stop onto the take-away conveyor, and die means for trimming the blank during said transfer from the feed conveyor to the take-away conveyor said stop arresting movement of the leading blank relative to said feed conveyor so as to maintain that blank in transverse registry with said die means until said transfer takes place.
- 25 2. Apparatus for automatically shaping blanks of soap or the like preliminary to die pressing comprising a feed conveyor for advancing a close succession of pre-cut blanks into said apparatus, a take-away conveyor at each side of the feed conveyor, a positioning stop in the path of the blanks on the feed conveyor, means movable across said feed conveyor and engaging each leading blank as the latter is positioned by said stop for transferring alternate blanks from said feed conveyor to the respective take-away conveyors, and die means for trimming the blanks during transfer from the feed conveyor to the take-away conveyors.
- 30 3. A soap trimmer comprising means for feeding a row of pre-cut soap bar blanks in close succession along a predetermined path, blank trimming dies on opposite sides of said path, and transfer means operable in timed relation with said feeding means for pushing alternate blanks of said row through said respective blank trimming dies.
- 35 4. A soap trimmer comprising a feed conveyor, a chute mounted at each side of said feed conveyor, said chutes having aligned openings above the level of said feed conveyor, trimmer elements mounted in said chutes in alignment with said openings, a stop in the path of articles on said feed conveyor for stopping articles in alignment with said trimmer elements, a reciprocating cross head mounted above said chutes, a soap pusher secured to said cross head, means to reciprocate said cross head and pusher, and means to convey trimmed cakes of soap ejected from said trimmer elements.
- 40 5. Apparatus for handling soap bar blanks and like articles comprising a continuously movable feed conveyor disposed between two take-away conveyors, trimming dies for said blanks disposed between said feed conveyor and each of said

take-away conveyors, and means operable in timed relation to said feed conveyor for transferring alternate blanks from said feed conveyor through said trimming dies onto the respective take-away conveyors.

6. Apparatus for handling soap bar blanks and the like comprising a continuously movable feed conveyor for advancing a succession of pre-cut blanks, a take-away conveyor adjacent said feed conveyor, a trimming die for said blanks disposed between said conveyors, means for stopping the leading blank on said feed conveyor in alignment with said trimming die, and means reciprocated across said feed conveyor for pushing said aligned blank from said feed conveyor through said trimming die onto said delivery conveyor, said feed

5 conveyor slipping beneath said leading blank when the latter is stopped in alignment with said trimming die.
